UNITED STATES PATENT OFFICE.

JOHN E. SEDERHOLM, OF ST. PAUL, MINNESOTA, ASSIGNOR TO AMERICAN HOIST & DERRICK COMPANY, OF ST. PAUL, MINNESOTA, A CORPORATION OF MINNESOTA.

ELECTRIC RIVET HEATER.

Application filed August 5, 1922. Serial No. 579,940.

To all whom it may concern:

Be it known that I, JOHN E. SEDERHOLM, a citizen of the United States, resident of St. Paul, in the county of Ramsey and State 5 of Minnesota, have invented certain new and useful Improvements in Electric Rivet Heaters, of which the following is a specification.

This invention relates to improvements in 10 electric heaters designed particularly for heating rivets for use in hot-riveting structural steel frames for buildings, bridges, etc.

The primary object of my invention is to 15 provide a rivet heater capable of being operated to full capacity, continuously and with a high degree of efficiency.

A further object of the invention is to 20 provide a rivet heater having each of its secondary coils or elements constructed of one piece, and, of practically an **E** form, so as to be in close proximity with the magnetic core, thus, allowing practically all of the magnetic lines of force, set up in the core by the primary coils, to act upon said coils 25 or elements when the circuit is closed.

A further object is to provide a rivet 30 heater having removably mounted jaws, or contact blocks, for holding the rivets, so that should the contacts become damaged from wear or arcing they may readily and quickly be removed for replacement without disturbing the secondary elements.

A further object is to provide a rivet 35 heater capable of heating rivets of various lengths without the necessity of adjustments, and also one in which a number of rivets may be heated simultaneously.

Other objects of the invention will more 40 fully appear from the following description and the accompanying drawings, and will be pointed out in the annexed claims:

The drawings disclose a structure designed to carry out the objects of the invention, but it is to be understood that the invention is not confined to the exact details or features shown, as various changes may be made within the scope of the claims 45 which follow.

In the drawings:

Figure 1 is a front elevation of an electric rivet heater embodying my invention.

Figure 2 is a transverse sectional view showing one of the secondary elements in

place on the magnetic core and the means for operating the rivet holding jaws. 55

Figure 3 is a top view showing the general arrangement of the different parts.

Figure 4 is a longitudinal sectional view on the line 4—4 of Figure 2 and showing the arrangement of the primary coils and the 60 secondary elements on the magnetic core.

Figure 5 is a fragmentary view of the insulated joint on one of the push rods for operating the upper jaws.

Figure 6 is a wiring diagram of the apparatus. 65

In the embodiment of the invention here shown, there is disclosed a frame consisting of a pair of front legs 7 and rear legs 8, preferably of angle iron. The front and rear leg on each side are preferably secured together near the bottom by a cross member 9 riveted thereto, and near the center section by a tie-rod 10. A magnetic core 11, constructed of laminated sheet steel, preferably rectangular in shape, is securely clamped between the front and rear legs, at the top, by bolts 12, thus providing a very rugged and substantial frame. 70

The upper and lower parallel longitudinally extending members of the magnetic core 11 are covered with a suitable insulating material 13. On the upper member of this core are mounted two primary coils 14, one adjacent each end, while on the lower member, and directly beneath the coils 14, two similar coils 15 are mounted. 75

Two secondary elements 16, preferably of copper and of substantially the letter **E** in form, (Fig. 2) are disposed upon the core 11, adjacent the primary coils, and are insulated therefrom by sheets of suitable insulating material 17, such as asbestos or interposed between said members, as shown in Figure 4. A bar 18, preferably of angle iron, has its ends secured to the rear of the frame by bolts 19, with its central portion bearing against the rear faces of the secondary elements, thus, securely clamping said elements in their respective places upon the magnetic core. This bar is also insulated from said elements by suitable insulation 21. The object of forming the secondary elements as above described is to provide an 80 element which will snugly fit the longitudinal member of the core, when mounted 90

100

105

thereon, as shown in Figure 2, thus greatly increasing the efficiency of the heater. I have here shown but two secondary elements, and four primary coils, but it is to be understood, however, that these may be varied in number and size depending upon the size and capacity of the apparatus desired. The primary coils are here shown as completely encircling the core sections on which they are mounted.

The forwardly extending upper and lower branches of the secondary elements are provided with vertical recesses or seats wherein contact blocks 23, are slidably mounted. These blocks are retained in their respective seats by stud bolts 24 secured to the forward faces of the elements and projecting forwardly through elongated apertures provided in said blocks. Guide or bearing plates 25, apertured to receive the ends of the bolts 24, are placed on said bolts and resiliently held against the contact blocks 23 by compression springs 26 and nuts 27. By the above means the contact blocks are held in close contact with the secondary elements at all times. An inwardly extending lug 28 is provided on each of the blocks 23 for use when heating long rivets, (Figure 1).

Two stationary contact blocks 29 are rigidly secured to the central portions of the secondary elements by bolts 31, and are arranged to be in a direct line with the upper and lower contact blocks 23, their inner portions projecting inwardly and co-operating with the lugs 28 in holding long bolts as shown in Figure 1.

The above construction provides a very simple and practical means for gripping and holding the rivets while they are being heated, and also should any of the contact blocks become damaged due to wear and arc-ing they may readily be removed for replacement without disturbing the secondary elements.

The two upper contact blocks are operated by means of foot pedals 32, pivotally mounted on a shaft 33, secured to the cross member 9 of the frame. These pedals have rearwardly extending arms 34, preferably integral therewith, to which connecting rods 35 are pivotally connected at 36, the upper ends of said rods being pivotally connected with the contact blocks as shown at 37. Coiled tension springs 38 are provided to yieldingly hold the contact blocks and the pedals in their normal position against a stop 39 secured to the frame. To prevent the foot pedals 32 from becoming energized when a rivet is inserted between the contact blocks for heating, it is necessary to insulate said blocks from the pedal connecting rods. This I have shown as being effected by providing a non-conductive, or insulated joint 41 in the connecting rods 35,

The two lower contact blocks are operated in a similar manner by foot pedals 42, also mounted on the shaft 33. Connecting rods 43 connect the pedals to the blocks and the springs 38 retain the blocks and pedals in their normal position against the stop 39.

A switch panel 44 is provided and preferably secured to one of the forward legs 7 within convenient reach of the operator. Upon this panel there is mounted a heat regulating switch 45, for regulating the temperature to which the rivets are heated, and also a control switch 46 for opening and closing the circuit to the main line. (Figures 1 and 6.)

The regulating switch 45 is provided with three contact posts 47, 48, and 49. (Figure 6.) The low heat post 47 is electrically connected by a conductor 51 to an electromagnet 52, and a conductor 53 connects the electromagnet to the main line wire 54. The medium heat post 48 is connected to the wire 54 by the conductor 55, electromagnet 56 and conductor 57, and the high heat post 49 is similarly connected by the conductor 58, electromagnet 59 and conductor 61. The regulating switch 45 is connected by a conductor 62 to a contact post 63 on the control switch 46.

A conductor 64 connects this switch to the main line wire 65. Thus, when the regulating switch 45 has been adjusted to the desired heat, as shown on the wiring diagram, (Figure 6) and the switch 46 is closed, a complete circuit will be formed: the current passing from the wire 65 through the conductor 64 to the switch 46, from the switch 46 through the conductor 62 to the switch 45, thence through the conductor 55, electromagnet 56 and conductor 57 to the main line wire 54. The above described circuits will hereinafter be referred to as the secondary circuits, as a matter of distinction between said circuits and the primary or heating circuits.

The primary circuits are provided with magnetically operated switches 67, 68, and 69, which automatically open and close through energization of the electromagnets 52, 56, and 59, in the secondary circuits. Thus, when the regulating switch 45 is in the position shown in the wiring diagram and the control switch 46 is closed, closing of the switch 68 will automatically be effected by the electromagnet 56. The current will be conducted from the main line wire 65 through a conductor 71, to the primary coils 14, through these coils to terminal posts 72, thence, through conductors 73, terminal posts 72^a connected with the primary coils 15. These latter coils are also provided with terminal posts 74, 75, and 76 corresponding to the three contact posts 47, 48 and 49 on the regulating switch 45. Thus when the switch 45 is in contact with the

medium heat post 48 as shown in Fig. 6 the current will flow from the coils 15 through the wires 77 and 78 to a terminal post 79 and thence through a conductor 81 to the switch 68, completing the medium heat circuit. The low and high heat primary circuits are similarly connected. Connectors 82 and 83 electrically connect the coils 15 to the switch 69, when high heat is desired, and conductors 84 and 85 connect the coils to the switch 67 when low heat is required.

From the foregoing, therefore, it will be noted that when the regulating switch 45 is in contact with the low-heat post 47, all of the ampere turns of the primary coils 15 will be in circuit which will reduce the amperage flow in the coils and cause said coils to become heated to a comparatively low temperature. Conversely, when the switch 45 is moved into contact with the high-heat post 49, a number of the ampere turns of the coils 15 will be cut out of the circuit, thereby increasing the amperage flow in said coils with the result that they will become heated to a relatively higher temperature or high-heat.

The operation of this apparatus may be explained as follows with reference to Figures 1 and 6:

30 First, the regulating switch 45 is adjusted to the desired heat. I have here shown it in contact with the medium heat post 48. The control switch 46 is then closed, allowing the current to flow through the medium heat primary circuit. As the current passes through the coils 14 and 15, the magnetic core 11, on which they are mounted becomes energized, said core in turn energizing the two secondary elements mounted thereon.

35 The voltage in the secondary elements is very low, being normally one volt, or less, but the current density very high, due to the current carrying capacity of said elements. Assuming now that a rivet is inserted between the upper right contact block 23 and the stationary block 29, (Figure 1), the current will flow from the block 23 through the rivet to the block 29, thence, around the magnetic core 11 back to the block 23, thus forming a complete circuit around the core. (Figure 6.) Owing to the inferior carrying capacity of the rivet due to its very low current density, it immediately starts to heat. As soon as it has attained the desired 50 degree of heat it is removed and the next rivet inserted. Rivets inserted between the lower contact blocks 23 and the stationary blocks 29 are heated in a similar manner, the current passing from the block 29 through the rivet to the block 23, thence, around the lower section of the core 11 and back to the blocks 29.

This apparatus is also adapted to heat rivets of considerable length without the necessity of mechanical adjustments. If it is

desired to heat rivets which are found to be too long to be inserted between the blocks 29 and 23, they may be inserted between the stationary block 29 and the lug 28 provided on the movable blocks 23 as indicated in Figure 1. The operation of the low and high heats is similar to that of the medium heat above described, differing only by increasing or decreasing the number of ampere turns in the primary coils 15 by tapping said coils as hereinbefore described. With this improved type of rivet heater, rivets of various diameters and lengths may be heated at one time thus greatly increasing the capacity and efficiency of the apparatus.

As here shown, the magnetic core 11 is in the form of a rectangular frame with the primary coils 14 arranged upon the upper longitudinal member of the frame, and the primary coils 15 upon the lower longitudinal member of said frame. The E-shaped secondary elements 16, 16, are each provided with three branches extending at right angles to the main or back member thereof. The center horizontal branch extends between the upper and lower longitudinal members of the core 11, while the upper and lower branches thereof extend one above the upper longitudinal member, and the other below the lower longitudinal member of said core 11. Said branches fit snugly against the walls of the core as shown in Figure 2. Each of said secondary elements may be considered as constituting a double U-shaped member, and the entire element is, therefore, of substantially E-shape. When a rivet is inserted, it completes a circuit either through the upper and middle branches of the secondary element, or through the lower and middle branches of said element, depending upon whether said rivet is placed above or below the block 29.

I claim as my invention:

1. In an electric rivet heater, the combination with a magnetic core in the form of a rectangular frame, of primary coils arranged on the longitudinal parallel members of said core, secondary elements of substantially E-shape, with their branches extending above and below the longitudinal members of said core, and means on the ends of said branches for holding rivets between the middle branch of said secondary element, and the upper or lower branch thereof.

2. In a device of the class described, the combination with a magnetic core, having longitudinally extending parallel members, of primary coils arranged on the parallel members of said core, secondary elements of substantially E-shape with their branches extending transversely above and below, and fitting against, the longitudinal members of said core, means for securing said

- secondary elements in position, and means on the ends of said branches for holding articles to be heated between adjacent ends of said branches.
5. 3. In a device of the class described, the combination with a magnetic core constructed of laminated sheet steel, and rectangular in form, of primary coils mounted on the upper and lower members of said core, a secondary element having branches projecting between, above and below the core members, a stationary block arranged upon the central branch of the secondary element, slidable contact blocks arranged upon the upper and lower branches of said element, and constructed to hold rivets, or similar articles, to be heated, between the stationary block and either of the slidable blocks, and means for moving said slidable blocks towards or from said stationary block.
10. 4. In a device of the class described, the combination with a magnetic core constructed of laminated sheet steel, and rectangular in form, of primary coils mounted on the upper and lower members of said core, a pair of secondary elements, each element having branches projecting between, above and below the core members, a stationary block arranged upon the central branch of each secondary element, slidable contact blocks arranged upon the upper and lower branches of each element, and constructed to hold rivets or similar articles to be heated between the stationary block and either 15 of the slidable blocks, and means for mov-
- ing said slidable blocks toward or from said stationary block.
5. In an electric rivet heater, the combination with a magnetic core, of primary coils, a secondary element having a central branch extending between an upper and a lower member of said core, and an upper and lower branch respectively above the upper member and below the lower member of said core, and means for holding rivets between the middle branch of said secondary element and the upper or the lower branch thereof. 40
6. In an electric rivet heater, the combination with a magnetic core, of primary coils arranged on longitudinal members of said core, secondary elements having upper, lower and middle branches extending above and below the longitudinal members of said core, and means on said branches for holding rivets between the middle branch of said secondary element and the upper or lower branch thereof. 45
7. In an electric rivet heater, the combination with a magnetic core, of primary coils arranged on said core, secondary elements of substantially E shape with their branches extending above and below the members of said core, and means on said branches for holding rivets between the middle branch of said secondary element and the upper or lower branch thereof. 50
